UNITED STATES PATENT OFFICE.

NIKON LEE AND ANTON P. STIANSEN, OF BROOKLYN, NEW YORK, ASSIGNEES TO
NATIONAL SEAL COMPANY, INC., OF BROOKLYN, NEW YORK, A CORPORATION OF
NEW YORK.

BOTTLE-SEALING MACHINE.

Application filed February 9, 1922. Serial No. 535,355.

Our invention relates to machines for applying and locking metallic seals or caps to the top openings in the necks of bottles, jars and similar types of containers, and is particularly devised and adapted for use in connection with the type of bottle-seal or cap shown and described in the two Benjamin W. Rivers Patents No. 1,304,098 of May 20, 1919, and No. 1,365,274 of January 11, 1921, the essential features of which are shown in diagrammatic form in the drawings accompanying this specification.

The objects of our invention are, among other things, to provide an improved and simplified machine of this character which will rapidly and securely lock the metallic seals or caps already loosely positioned on the open rims of the necks by twisting or partially rotating such seals or caps on the rim of the bottle neck so that the inturned portions or lips of the depending flanges or skirts of the seal or cap may firmly and securely engage with the spaced-apart lugs formed on the outside of the bottle neck by a special mechanism and attachments controlled, but not operated, by a foot-operated pedal which allows the particular devices for locking the cap to come successively into operation.

Our improved machine is also devised so as to be readily adjusted to bottles of different heights having neck openings and seals of different diameters, and embodies improved means for gripping and releasing the bottles in each cycle in suitable timed relation with the devices for applying and locking the seals or caps in final position.

Our improvements also comprise the construction and arrangement of operating parts herein shown and hereinafter to be described as preferred embodiment of our invention, and then particularly pointed out in the appended claims.

In the accompanying drawings, Fig. 1 is a vertical sectional view, partly in elevation, of our improved machine showing the general arrangement of the parts;

Fig. 2 is an enlarged sectional plan view taken on the line 2—2 of Fig. 1 looking in the direction of the arrow;

Fig. 3 is a view similar to Fig. 2, but taken on the line 3—3 of Fig. 1 looking in the direction of the arrow;

Fig. 4 is a detail view of the bottle-gripper jaws in open position;

Fig. 5 is an enlarged fragmentary sectional plan view taken on the line 5—5 in Fig. 9;

Fig. 6 is a view similar to Fig. 5 taken on the line 6—6 in Fig. 9;

Fig. 7 is a diagrammatic view of the action of the cam for lowering the seal or cap applying devices;

Fig. 8 is a diagrammatic view of the cam for partially rotating or twisting the cap applying devices to lock the cap in final position on the bottle neck;

Fig. 9 is an enlarged vertical sectional view of the head which carries the cap applying devices, the seal or cap chuck being closed;

Fig. 10 is a fragmentary sectional view showing the seal or cap chuck open;

Fig. 11 is a detail side elevation of a bottle neck;

Fig. 12 is a top plan view thereof;

Fig. 13 is a bottom plan view of a seal or cap arranged to be applied to the open end of the bottle neck shown in Fig. 11;

Fig. 14 is a diagrammatic view, partly in section, showing the seal or cap as applied to the bottle neck;

Fig. 15 is a diagrammatic view, partly in section, showing the cap after it has been turned or twisted into final locking position.

Fig. 16 is a bottom plan view of seal or cap chuck showing the cap-clamping jaws;

Fig. 17 is an enlarged sectional plan view showing the operating clutch in disengaged position;

Fig. 18 is an enlarged top plan view of the clutch shown in Fig. 17, the parts being in engaged position;

Fig. 19 is an enlarged sectional view taken on the line 19—19 in Fig. 17;

Fig. 20 is an enlarged sectional view taken on the line 20—20 in Fig. 17;

Fig. 21 is a sectional view taken on the line 21—21 of Fig. 17;

Fig. 22 is a fragmentary detail view of one of the clutch members; and

Fig. 23 is a perspective view of the clutch dog.

Similar numerals refer to similar parts throughout the various figures.

Referring more particularly to Fig. 1, the

stand 24 carries the vertical shaft 25 which is journalled in the table 26, the upper end being mounted in the journal 27 carried by the head 28 secured to the top of the stand 24 as shown. The lower end of the shaft 25 is supported by the heel bearing 29 carried by the bracket 30 secured to the stand 24. The shaft 25 is devised to be intermittently rotated by a clutch made up of two parts, 10 the upper member 31 being affixed to the shaft 25 by key 32, while the lower member 33 is loosely journalled upon the shaft 25 and has secured thereto the gear 34 (Fig. 21) in mesh with the bevel gear 35 which 15 in turn is operated by a train of gears 36, 37, 38, 39 and a motor 40 mounted on the bracket 41 secured to the stand 24, all as shown in Fig. 1.

The lower clutch member 33 comprises the 20 hollow disk 42 carrying in its periphery spaced-apart lugs 43 to provide openings 44 therebetween to receive and engage a spring-impelled dog 45 slidably mounted in the guideway 46 carried by the upper clutch member 31 as shown in Figs. 17, 18, and 19. The dog 45 is normally held out of engagement with lower clutch member 33 by the wedge plate 47 mounted on the head 48 carried by the vertically movable rod 49 which 25 is operated by the pedal 50 and link 51 as shown in Fig. 1. The spring 52 coiled about the rod 49 as shown maintains this head 48 and wedge plate 47 normally in their lower position as shown in full lines in Fig. 19, and the dog 45 will then bear against the lip 53 formed in the plate 47 (Fig. 17), the inclined surface 54 on the plate 47 holding the dog 45 pressed inwardly against the tension of the coil spring 52, whereby the 30 clutch member 33 can freely rotate on the shaft 25. To lock the two clutch members 31 and 33 into operative engagement, the operator will depress the pedal 50 thereby raising the head 48 and wedge plate 47 to 35 clear the dog 45 as indicated by dotted lines in Fig. 19. Thereupon the spring 52 will force outwardly the dog 45 carried by the upper clutch member 31 to engage one of the openings 44 in the constantly rotating clutch member 33 which will then be rotated with the shaft 25 through the train of gears driven by the motor 40 as heretofore described. When the shaft 25 begins to rotate the 40 pedal 50 will be released by the operator, and the wedge plate 47 will drop into the circular path of the dog 45. As the dog 45 is about to complete its single revolution, it will be forced out of its opening 44 (Fig. 18) by its nose striking the inclined surface 54, and the shaft 25 will cease its rotary movement through the disengagement of the clutch members 31 and 33. By this mechanism the shaft 25 is intermittently rotated by the pedal 50 under the control of the 45 operator, and is then automatically thrown

out of operation. The improved devices for applying the seal or cap to the bottle necks are successively actuated during a single revolution of the shaft 25 in each cycle.

The devices for applying such seals or 70 caps to the bottles comprise the head 55 which is vertically adjustable on the shaft 25 by the lead screw 56 engaging the stand 24 and screw-threaded sleeve 57 mounted in the lug 58 carried by the head 55, the screw 56 75 being turned by the hand-wheel 59, all as shown in Figs. 1 and 9. This vertical adjustment of the head 55 relatively to the table 26 enables our machine to accommodate bottles of different heights. Referring 80 more particularly to Fig. 9, the head 55 supports the vertically movable sleeve 60 connected to the block 61 slidably mounted within the bore 62 of the head 55. The block 61 carries the roller 63 which projects 85 outwardly through the vertical slot 64 and bears on the circular cam 65 keyed to the shaft 25. The block 61 and sleeve 60 are connected by the stud 66, the head 67 of which is engaged by the lower end of the coil spring 68, while the upper end of the spring 68 engages the adjustable disk 69 arranged in the upper part of the head 55. The spring 68 acts to hold the roller 63 on the cam-runway 65 as well as to restore the 95 bottle-seal or cap-applying devices to their normal or original position after they have been partially rotated or twisted to lock the cap in position by the revolution of the shaft 25 due to the torsional stress thereby 100 imparted to the spring 68.

The devices for gripping the cap and twisting same comprise the cap chuck 70 having the four spring clamping jaws 71 (Fig. 16) integrally secured to the head 72 105 screw-threaded in the collar 73 which is slidably mounted in the sleeve 60 and is keyed thereto by the key 74 (Figs. 6 and 9). The jaws 71 engage the cylindrical seal or cap 75 which has theretofore been applied by 110 an operator to the rim of the neck of the bottle 76 as shown in Figs. 9 and 10. The spring 77 arranged between the top of the sleeve 60 and the collar 73 acts to force the chuck 70 downwardly so that the jaws 71 115 may surround and grip the cap 75. The outer wall of the sleeve 60 is provided with vertical teeth 78 (Figs. 6, 9 and 10) which are engaged by teeth 79 on rack-lever 80 pivoted at 81 to the head 55. The arm 82 120 of the rack-lever 80 carries the cam-roller 83 bearing upon the cam 84 keyed to the shaft 25 as shown in Figs. 5 and 6. When the shaft 25 is rotated the sleeve 60 and cap chuck 70 will lower together until the jaws 71 125 engage the cap 75 on the bottle 76 held on the table 26 by the bottle gripper jaws 85 and 86 on the table beneath the chuck 70, the jaw 86 being slideable on the table 26 so as to grip bottles of different diameters. 130

When the chuck 70 is in its raised position the jaws 71 will be extended as shown in Fig. 10, the spring 77 acting to maintain the chuck and jaws in their extended open position in readiness to engage the cap 75. At this time the roller 63 will be riding in the high part of the cam 65 (Fig. 7). However when the cam 65 is revolved sufficiently to cause the roller 63 to drop into the depression 87 formed in the cam 65 (Fig. 7), the sleeve 60 and chuck 70 will be forced downwardly by the spring 68, and the jaws 71 will remain open about the cap until forced against the cap 75, after which the sleeve 60 will continue to move downwardly and close the jaws 71 securely against the cap 75. The spring 68 is made to have greater tension than the spring 77 and hence will overcome the force of the latter after the chuck 70 contacts with the cap 75 as shown in Fig. 9. After the sleeve 60 has closed the clamping jaws 71 upon the cap, the rack-lever 80 will be rocked by the cam 84 to rotate or twist both the sleeve 60 and chuck 70 in a clockwise direction (Figs. 5 and 6) to force the inturned portions or lips 88 of the cap 75 (Fig. 13) under the locking lugs 89 on the neck 90 of the bottle 76, that is to say, from the position shown in Fig. 14 to that shown in Fig. 15. In partially rotating the chuck 70 the spring 68 has thereby been twisted and placed under torsional stress so that as the sleeve 60 is raised by the cam-roller 63 riding up on the high part of the cam 65 to raise the head 55 during that part of the cycle when the cam-roller 83 is travelling over the curved elongated part of the cam 84; at this time the chuck 70 and jaws 71 will be lifted and freed from the cap 75 and will simultaneously turn back to normal position by the torsional stress of the spring 68 when released by the uplifted sleeve 60 as the roller 83 rides off the high part of cam 84.

The bottle gripper jaw 86 is operated in suitable timed relation with the cap applying devices by the following mechanism: Referring to Figs. 1 and 2, the lever 91 is pivotally secured to the underside of the table 26 by the pin 92, and is actuated by the cam 93 keyed to the shaft 25, the cam 93 bearing on the roller 94 carried by the lever adjacent the pin 92. The compression spring 95 coiled within the telescoping tubular links 96 and 97 serves to hold the roller 94 against the cam 93, and also to hold yieldingly the jaw 86 against the bottle. The outer end of the lever 91 is forked at 98 to engage the stud 99 secured to the jaw 86 and projecting downwardly through the slot 100 formed in the table 26. The cams 65 and 93 are so keyed to the shaft 25 that the cam 93 acts first to cause the jaw 86 to slide inwardly through the spring 95 to yieldingly grip the bottle 76 after the bottle has been placed in position by the operator between the jaws 85 and 86, as is shown in Fig. 4. Then the rotating cam 65 acts to allow the spring 68 to lower the sleeve 60 and chuck 70 as heretofore described. After the chuck 70 has lifted the jaw 86 opens to release the bottle 76, all of which occurs during a single revolution of the shaft 25, as the latter will cease rotating when the dog 45 rides up the inclined surface 54 and strikes the lip 53 of the plate 47. To relieve the impact of dog 45 and lip 53 the head 48 carries the spring-pressed button 101 which is forced inwardly against the spring 102 by the wedge-plate 47 when the rotating dog 45 strikes the lip 53 as shown in Fig. 17. To lock the rod 49 against vertical movement a stop-pin 103 passes through the stand 24 to engage the recess 104 formed in the head 48 as shown in Fig. 1.

The operation of the hereinbefore described mechanism during a cycle is substantially as follows: The bottle 76 with the cap 75 applied thereto as shown in Figs. 10 and 14 is placed in the table 26 between the two gripper jaws in the position shown in dotted lines in Fig. 4. The operator then depresses the pedal 50 which releases the dog 45 from engagement with the lip 53 and such dog engages one of the openings 44 in the clutch member 33 which starts the rotation of the shaft 25 and the pedal 50 is immediately released by the operator. First the gripper jaw 86 is released by the cam 93 and is pressed yieldingly against the bottle 76 by the spring 95. Thereafter the rotation of the cam 65 allows the spring 68 to force downwardly the chuck 70 with its clamping jaws 71 to engage the cap 75 along with the sleeve 60 from the position shown in Fig. 10 to that shown in Fig. 9. Then the cam-roller 83 rides up the high part of the cam 84 to operate the rack-lever 80 to engage the teeth 78 of the sleeve 60 to rotate the latter in a clockwise direction (Figs. 5, 6 and 8), which twists or turns the cap 75 from the position shown in Fig. 14 to that shown in Fig. 15 whereby the lips 88 of the cap 75 will engage the lugs 89 on the bottle 76. Such twisting movement of the sleeve 60 also places the spring 68 under torsional stress so that when the roller 83 rides off the high part of the cam 84, the roller 63 will ride up the high part of the cam 65 to cause a combined lifting anti-clockwise movement of sleeve 60 and chuck 70 to restore same to original position while freeing the jaws 71 from engagement with the cap 75. As the clutch member 33 is about to complete its revolution the cam 93 actuates the lever 91 (Fig. 2), to retract the gripper jaw 86 to the position shown in Fig. 4 whereupon the operator removes the bottle 76, and the dog 45 moves from the position shown in Fig. 18 to that in Fig. 17 when the clutch mem-

bers 31 and 33 are disengaged and the cycle of operation is completed.

While the construction herein described embodies the invention in its preferred form, it will be understood that changes and variations may be made in the various parts without departing from the principles and scope of the invention.

We claim as our invention:

10. 1. In a bottle-sealing machine, coacting laterally-moving grippers for holding a bottle and seal cap positioned thereon in horizontal position, a superposed coacting sealing head comprising a vertically movable seal clamp also laterally rotatable therein, cam-controlled spring-pressed means for lowering said clamp to positively grip the seal on the bottle, means for thereafter partially rotating said clamp in a horizontal plane 15 when lowered and gripping said seal relatively to said head and bottle in one direction, a spring for reversing the rotation of said clamp during its lifting movement, a source of power, and a clutch driven by said 20 source of power and operable to clutching position by the operator for connecting said seal gripping means and said clamp rotating means with said source of power in sequence to place said spring under torsional 25 stress during the continued movement of the machine.

2. In a bottle-sealing machine, coacting laterally-moving grippers for holding a bottle and seal cap positioned thereon in a fixed 35 horizontal position, a superposed coacting sealing head comprising seal-clamping jaws separately rotatable in, and vertically movable relatively to, said head for positively gripping the seal already positioned on the 40 bottle, means for lowering said jaws to engage the seal, means for thereafter twisting said jaws in a horizontal plane when engaging a seal relatively to said head and bottle, a spring for reversing the rotation 45 of said jaws during their lifting movement, a source of power, and a clutch operable to clutching position by the operator for connecting said seal gripping jaws and said jaw twisting means with said source of power in sequence to place said spring under torsional stress through the continued operation 50 of the machine.

3. In a bottle-sealing machine, means for holding a bottle having a seal positioned 55 on the bottle-opening in a fixed position, a co-acting sealing head carrying a plurality of vertically movable clamping-jaws and coacting sleeve for positively gripping the seal when lowered into engagement therewith, means for partially rotating said jaws

and coacting sleeve and seal relatively to said bottle and head and horizontally in one direction, means for raising said jaws from the seal, means for reversing the rotary movement of said jaws and permitting the release of same from engagement with said seal while being raised, and means controlled by the operator for sequentially actuating each of said means through the continued operation of the machine.

4. In a bottle-sealing machine, a fixed holder adapted to grip a bottle having a seal positioned on the bottle opening, vertically movable seal-gripping means arranged over said holder for positively gripping the seal, means controlled by the operator for thereafter twisting said seal-gripping means in a horizontal plane, means operable through the continued movement of the machine to simultaneously release said seal-gripping means and means to simultaneously reverse said twisting means.

5. In a bottle-sealing machine, means for holding a bottle in a fixed position with a seal positioned on the bottle opening, a co-acting sealing head having vertically movable clamping jaws for gripping said seal, means for twisting said seal-gripping jaws in one direction in a horizontal plane, a spring placed under compression for reversing said clamping jaws, means for releasing said bottle holding means, a rotary shaft operatively connected with each of said means, a source of power, a clutch controller by the operator for rotatably connecting said shaft with said source of power whereby said twisting means and said releasing means are automatically actuated in sequence, and means for automatically disconnecting said clutch after the operation of said releasing means.

6. In a bottle-sealing machine, a bottle-holder, a coacting sealing-head having vertically movable means for positively gripping a seal positioned on the bottle opening, means for thereafter twisting said seal-gripping means in one direction and in a horizontal plane to lock the seal on the bottle, means for reversing said twisting means, an actuating member for each of said means, a source of power, a clutch driven thereby for intermittently connecting said member with said power to successively actuate said means, and means for automatically disconnecting said clutch **at the end of each cycle** 110 actuated through the continued movement of the machine.
